Specification of Letters Patent. Patented Nov. 20, 1917.

Application filed March 17, 1915. Serial No. 14,922.

To all whom it may concern:

Be it known that I, FRANCESCO RENZO, a subject of the King of Italy, residing at Paterson, in the county of Passaic and State 5 of New Jersey, have invented certain new and useful Improvements in Shuttles, of which the following is a specification.

The object of this invention is to provide a loom shuttle which, while possessing practically all of the advantages attendant upon the use of the ordinary wood shuttle, shall be proof against the development or forming therein of splits, dents or the like and which shall at the same time be capable of 15 being produced at the least possible increased cost of manufacture.

In the accompanying drawings, in which the invention is fully illustrated in its preferred form,

20 Figure 1 is a plan view of the improved shuttle;

Fig. 2 is a side elevation thereof;

Fig. 3 is a cross-section on the line $x-x$ in Fig. 2;

25 Figs. 4 and 5 are perspective views of the jacket and core in their original forms; and,

Fig. 6 is a perspective view of the jacket, core and tip elements, assembled and before the exterior of the shuttle has been trimmed 30 to its ultimate form.

The core a shown in Fig. 5 is a suitable length of wood preferably having its top and bottom surfaces on the one hand, and its two side surfaces on the other, parallel with 35 each other, excepting that as to one or more of said surfaces, preferably the two side surfaces, bevels are formed, as shown, to give the core a certain amount of taper at the ends thereof.

40 The jacket or shell b , which in its ultimate condition as a part of the shuttle is a tough, grainless and light material, is preferably formed by softening a sheet, say of fiber, and then pressing the same in a suitable mold in the shape shown in Fig. 5, which shape interiorly of the jacket conforms to the shape of the core a . The length of the jacket in the preferred form is 45 coextensive with that of the core, which has 50 its ends cut off square.

The jacket having been thus formed and preferably allowed to set until it resumes its original state of hardness, and glue or other cement c having been applied to all of the

inside surface of the jacket, or all of the 55 corresponding surface of the core, or to both, the core is placed in the jacket and then the parts subjected to pressure so that their opposed surfaces at all points are held in intimate contact with each other throughout; 60 in this condition, the parts are left until the cement has set. The shell being open from end to end thereof (in the adaptation shown, from one side clear to the other side thereof), the assembling operation is one 65 which is at once of the simplest character and may be made to result in the shell being shaped, even at the tapered ends of the shuttle, exactly to the form of the core.

Thereupon, the core is chambered, as at 70 c , for the filling package and the tension means d and the holes e are driven through the jacket and core for the reception of the pins f which support the spindle g and its spring h . In the preferred construction, 75 the pins f are made a trifle longer than the core is thick, so that their ends rest in the side walls of the jacket, as shown in Fig. 3. Then the tip elements are attached to the end of the core, each such tip element including a tapered metallic tip proper i and a washer or disk j (preferably of fiber), through which the tang of the tip proper i is driven.

Finally, the outer surface of the body thus 85 formed is trimmed to the ultimate shape of the shuttle and polished, the sides and bottom of the jacket and the top surface of the core being made flush with the tip elements.

Since the two side and bottom walls of 90 the jacket of the improved shuttle are integral with each other, there is no possibility for open seams to form lengthwise of the shuttle and along its edges, and particularly the bottom edges, due to the cement being 95 ineffective to keep the jacket walls bound to the core under the stress of violent shocks and friction to which the shuttle is constantly subjected. The jacket, by having its two side and bottom walls integral in the 100 vicinity of the pins f , and especially where the ends of the pins rest in the side walls of the jacket, further reinforces the core of the shuttle against splitting on account of shocks or strains incident to moving the 105 spindle on its pivoting pin; shuttles of ordinary construction often split lengthwise at one or other of these pins, and such splitting

is wholly avoided in the improved shuttle. Finally, the core approximating in length the length of the shuttle, the structure is in effect a jacketed shuttle, as such having the 5 obvious advantage over the heretofore-proposed shuttle-shaped shell carrying in its ends separated core pieces for the support of the spindle and other parts that the ends of the core are solidly connected and the 10 whole structure is therefore perfectly adapted to withstand the shocks attending its back and forth movements in the loom.

It is preferable, as herein described and shown, to taper the ends of the core, since 15 thereby, when the trimming of the ends of the shuttle is effected, there will be sufficient thickness of material in the jacket so that upon the trimming being accomplished there will be no exposing as the result thereof of 20 the core.

Having thus fully described my invention, what I claim as new and desire to secure by Letters Patent is:—

1. A loom shuttle including an elongated 25 chambered core extending approximately from end to end of the shuttle and an elongated one-piece shell of hard, stiff, sheet material jacketing and secured to said core and including a bottom and two side walls 30 covering said core at the bottom and both sides from approximately end to end there-

of, said shell being open from end to end thereof at the upper side.

2. A loom shuttle including an elongated chambered core extending approximately 35 from end to end of the shuttle and an elongated one-piece shell of hard, stiff, sheet material jacketing and secured to said core and including two or more adjoining walls covering said core at two or more adjoining 40 surfaces thereof from approximately end to end of said core, said shell being open from end to end thereof.

3. A loom shuttle including an elongated chambered core extending approximately 45 from end to end of the shuttle and an elongated one-piece shell of hard, stiff, sheet material jacketing and secured to said core and including two substantially parallel walls and a third wall joining the parallel 50 walls, such three walls covering said core at three adjoining surfaces thereof from approximately end to end of the core and said shell being open from end to end thereof.

In testimony whereof I affix my signature in presence of two witnesses.

FRANCESCO RENZO.
